MICROSCOPE

Paul A. Hoogesteger, Brighton, N.Y., assignor to
Bausch & Lomb Incorporated, Rochester, N.Y., a
corporation of New York

Filed Mar. 22, 1963, Ser. No. 74,092

Term of patent 14 years

(Cl. D57—1)

FIG. 1 is a front perspective view of a microscope embodying my new design; and

FIG. 2 is a rear perspective view thereof.

The dominant features of my design reside in the portions shown in full lines.

I claim:

The ornamental design for a microscope, substantially as shown and described.
